UNITED STATES PATENT OFFICE

MARK R. GILSON, OF MAPLE SHADE, NEW JERSEY

POSITIONING DEVICE FOR FLASH LIGHTS

Application filed August 7, 1929. Serial No. 384,093.

This invention relates to a flash light supporting device and particularly to a device which will enable the flash light to be secured to any part of the clothing of the user so that the rays from the light may be directed onto the work regardless of the location and which, when so directed, will enable the user to have the free use of both hands for performing his task.

10 The object of the invention is to provide an improved device having the above characteristics.

Another object is to provide such a device with the above mentioned attributes which 15 may be economically manufactured and which is practically incapable of getting out of order and which need never be removed from the flash light body.

According to the invention, the device comprises two broken circular members of spring sheet steel connected together by means of a hinge, and one of these is adapted to substantially encircle the light body, while the other, which has its unconnected end rolled, 25 is adapted to be snapped down over the other member and with the supporting means between the same.

The drawing illustrates an embodiment of the invention and the views therein are as 30 follows:—

Figure 1 shows the manner of supporting one type of flash light upon the clothing of the user,

Figure 2 is a perspective view of the device,

Figure 3 is a cross-sectional view showing the manner in which the portion of the clothing is securely maintained between the members, and

Figure 4 illustrates the manner of connecting another type of flash light to the belt worn by the user.

The device comprises an inner flat strip of spring metal bent to form a split band 6 and having a substantial opening between the opposed ends thereof so that it may be readily applied to embrace the body of a flash light, and one of its ends is recessed at the point 7 while the end portions 8 and 9 are rolled so that when the rolled portion 11 of the

outer split band 12 is placed in the recess 7 and the pintle 13 extended through the same, the bands 6 and 12 are securely hinged together.

The other end of the band 12 is rolled, as at 55 14, so that it can slide easily over the end 16 of the other split band when that band is applied to the desired position on the flash light body.

In Figure 1, the flash light 17 illustrated is 60 of that type which has the lens extending out from the side of the same, while the flash light 18, shown in Figure 14, has the lens located in one end. With either of these types the device is equally effective and it is intended 65 that the band 6 shall always remain applied to the light body, and when it is desired to attach the same to the collar, lapel or other portion of a coat, to shirt front, sleeve or to a part of the trousers or belt of the user, the 70 part of the garment, which I have marked 19, rests between portions of the two bands, as shown in Figure 3, and as the bands are substantially of the same diameter and the band 6 being somewhat spread by the flash 75 light body, the inclusion of the part of the garment 19 will further spread the outer band 12 and therefore provide an effectual grip which is almost impossible to accidentally break.

Of course, the band is made of spring metal whose modulus will never be reached in the normal operation of the device and, consequently, the spring tension of both bands will remain practically the same regardless of 85 the length of the service.

It follows that the device illustrated may be modified in various ways without departing from the invention herein set forth and hereafter claimed.

The invention is hereby claimed as follows:—

1. A flashlight positioning device comprising a pair of substantially circular spring bands hinged together so as to permit one 95 to be snapped around the other.

2. A flashlight positioning device comprising a pair of substantially circular spring bands having one end of each formed to provide a hinge between the bands so as to 100

permit one to be snapped around the other.

3. A flashlight positioning device comprising a spring band for encircling a flashlight body, a similar spring band hinged at one end to one end of said first band and adapted to be snapped over the first band to securely grip a supporting member between the bands.

10 4. A flashlight positioning device comprising a spring band for snapping onto and encircling an outer spring band, a hinge formed between one of the ends of each band, the other end of the outer band being rolled to permit it to slide readily over a support to be included between the bands.

15 5. A flashlight positioning device comprising a spring band for snapping onto and encircling an outer spring band, a hinge formed between one of the ends of each band, the other end of the outer band being rolled to permit it to slide readily over a support to be included between the bands, said outer band being adapted to securely grip the support when it snaps into position encircling said first band.

20 In testimony whereof I have signed my name to this specification.

MARK R. GILSON.
